 By his Atty. I. Dennis

UNITED STATES PATENT OFFICE.

HARRY WHITE, OF ONEIDA CASTLE, NEW YORK.

IMPROVEMENT IN SHINGLE-MACHINES.

Specification forming part of Letters Patent No. 56,648, dated July 24, 1866.

To all whom it may concern:

Be it known that I, HARRY WHITE, of Oneida Castle, Oneida county, State of New York, have invented certain new and useful Improvements in Shingle-Machines; and I do hereby declare the following description and accompanying drawings are sufficient to enable any person skilled in the art or science to which it most nearly appertains to make and use my said invention or improvements without further invention or experiment.

The nature of my invention and improvements consists in certain improvements on the shingle-machine patented to me on the 27th day of May, 1856, No. 14,977, by which improvements I have remedied the defects in the machine then patented and perfected it.

These improvements may be enumerated as follows: in providing an automatic feeding-plate, to feed the blocks to be shaved just at the proper time when they are required and in a forked spring-guide arranged to guide the upper ends of the blocks as they are fed into the machine into the proper position to be properly shaved on both sides; and in providing the clamping-plates with arms and adjusting-screws to steady and support them when the machine is in operation; also, in certain devices for springing and holding the shaving-knives, so as to shave the shingle as thick eight or ten inches from the butt as it is shaved at the butt.

In the accompanying drawings, Figure 1 is an elevation of my machine for shaving shingles. Fig. 2 is a plan or top view; Fig. 3, an elevation of one end. Fig. 4 is the forked rod, and Fig. 5 the connecting-link.

In these drawings, A A' are top and bottom frames, made of cast-iron or other material in the form shown, or in such other form as will answer the purpose. These frames are connected by the bars B B B, which hold them a proper distance apart horizontally, as shown in Fig. 1. On the under side of the main bar of the top frame, A, there are two ways or rails, C, and the same on the upper side of the frame A'. Between these rails C C perpendicularly the carriage is fitted to traverse horizontally, which consists of two frames, D D, with grooved edges to fit the ways, which frames are connected by the bolt E, which

passes through them and through the end of the link F, which connects the carriage to a crank of some moving power to operate the machine.

G is a strong bar of metal fastened centrally between the frames A A', to stop and hold the bolts of wood while they are being shaved to make shingles. This bar G is made thinner than a shingle, so that the knives H, fastened to the carriage, can pass freely by on each side without contact with it. The knives H are set inclined, as shown in the drawings, and begin to cut at one corner of the shingle at the thick end, and finish cutting at the opposite corner diagonally at the thin end, of the shingle, so as to shave them smooth. These knives H are fastened to the carriage D and adjusted by the screws I. The screw K passes through the frame and through the knife H, to draw the middle of the knife toward the frame and curve it to shave the shingles and leave them as thick one-third or one-half the way from the butt toward the point as they are at the butt.

The screw above the screw K is screwed against the knife to prevent it from springing and hold it firmly. The pieces J are fastened to the lower bars of the frames D by screws L L, to adjust them at an angle to each other and form a trough to receive the ends of the blocks to be shaved, and the inclination of the pieces J brings the end of the block in the center between them.

To hold the shingle or block in the proper position and carry one edge to the bar G, there are two pieces like N, with their lower ends fastened to the lower part of the carriage, so that the upper ends will swing out between the pins M M when they pass onto the wedges P, fastened to the sides of the frame A.

The horizontal clamping-plates Q are fastened to the pieces or levers N, and are pressed against the block by the springs S S, fastened to the lower bar of the carriage, as the ends of the levers N pass off of the wedges P, so as to clamp the block in the center of the carriage and carry it against the bar G to be shaved. The arms R R are fastened firmly to the plates Q Q, and extend up onto the upper bar of the frames D, with set-screws in their upper ends, to stop the clamping-plates Q a

proper distance each side of the center, and so that they will pass back by the bar G after the shingle is shaved without touching the bar.

The plates T are fastened on the top of frame A to form ways for the feeding-plate V to traverse between. This plate V covers the feeding-hole W, and holds up the block which is placed upon it until the carriage runs back and carries the wedge U (shown in dotted lines in Fig. 2) under the lug X on the feeding-plate, which is moved back and drawn from under the block, which drops into the carriage with its lower end between the pieces J, and as the wedge U is fastened to the upper end of the lever N, when the carriage is run forward the wedge is moved, and the feeding-plate V is drawn over the hole W by the springs Y Y, (shown by dotted lines in Fig. 2,) under the arms V' of the plate V, which arms V' have their outer ends turned down and perforated to traverse on the pins in the frame A, around which pins the springs Y are placed.

To hold the blocks perpendicular over the feeding-hole W, the plates T are perforated for the stands a a, (shown by dotted lines in Fig. 1,) to which stands the board Z is fastened so as to stand perpendicularly beside the feeding-hole, and the cleat b on the board at the end of the feeding-hole; and to hold the block upright by the side of the board Z a plate of sheet metal, Z', is fastened to the board and bent over and turned down, so as to stand off from the board far enough for the upper end of the block placed on the feeding-plate to stand between the plate and the board when placed there by the attendant to feed the machine.

To guide the upper end of the block to the bar G the rod c is arranged to traverse in the stands d d under the frame A. This rod c is made in the form shown in Fig. , with a forked end to pass each side of the bar G, and the ends of the prongs are made flaring to receive the edge of the block and guide it centrally against the bar G, the rod being pushed

back by the block against the spring e, and to move the end of the rod out of the way of the knives the long nut f is put upon it, so that when the carriage runs forward it strikes the nut f and moves the ends of the rod out of the way of the knives.

The clamping-plates g g are arranged behind knives to seize the shingle after it is shaved. These plates are held and pressed together by the springs h h fastened to the frames D, and they carry the shingle out of the machine when they are spread by the post j to let the shingle drop.

The machine having been constructed as described and power applied to traverse the carriage, the attendant places a block on the feeding-plate (V) side of the board Z, with its upper end behind the plate Z', and as the carriage is run back the wedge U draws the plate V from under the block, and it drops through the feeding-hole W with its lower end between the plates N, and when the carriage moves forward the clamping-plates Q close upon the block and carry it against the bar G, the rod c receiving and guiding the upper corner. The plates Q slip off of the block as it is shaved, and the plates g behind the knives seize the shingle and carry it out of the machine and let it drop at the same time that a block is dropped through the feeding-hole W, and the operation is repeated.

Having described my improvements, I claim—

1. The combination and arrangement of the automatic feeding-plate V, the forked guide-rod c, and the adjusting-arms R R, the whole being arranged for joint operation substantially as described.

2. Adjusting the knives to shave the shingles in the form described by the means substantially as described.

HARRY WHITE.
